CLAIM

I claim the ornamental design for a bag clip, as shown and described.

DESCRIPTION

FIG. 1 is a perspective view of a bag clip showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In these drawings, the solid lines illustrate the claimed ornamental design, whereas broken lines form no part of the claimed design.
